UNITED STATES PATENT OFFICE.

ISAAC D. COMSTOCK, OF ADRIAN, MICHIGAN.

CHAIR-SEAT.

SPECIFICATION forming part of Letters Patent No. 270,748, dated January 16, 1883.

Application filed March 4, 1882. (Model.)

To all whom it may concern:

Be it known that I, ISAAC D. COMSTOCK, of Adrian, in the county of Lenawee and State of Michigan, have invented new and useful 5 Improvements in Chair-Seats; and I hereby declare that the following is a full, clear, and exact description thereof, reference being had to the accompanying drawings, which form a part of this specification.

10 The nature of this invention relates to certain new and useful improvements in the construction of chair bottoms or backs of that class in which the seats and backs are constructed of interwoven cane.

15 The object of the invention is to produce a better effect than that produced by the ordinary mode of weaving cane, wherein the cane is carried entirely around the top and bottom of the seat, and with less cane.

20 The invention consists in the peculiar construction of the rounds, and in the manner of weaving the cane around and securing it to the same, as more fully hereinafter described and claimed.

25 In the accompanying drawings, Figure 1 represents a portion of the chair-seat with the ends of the canes turned back to show the "kinks," and Fig. 2 a modification.

30 A designates portions of the chair-legs, and B grooved rounds secured thereto, forming a square frame, commonly known as the "seat-frame." The grooves *a* in the rounds B extend the entire length of said rounds, and are preferably, for convenience in weaving the cane, 35 made upon the outer faces of the rounds, although they may be made at any other point. These grooves are of about the same width as the canes to be used.

35 C represents the canes, which are woven 40 around and secured to the rounds in the following manner:

45 One end of a single cane is inserted, face inward into the chair-leg in the groove of the round, and the cane is then twisted to form a kink and to bring its face to the outside, and is then passed once around the round to press and keep the twisted or kinked portion into the groove in the round. The cane is then carried to the opposite round, and over and 50 around the same until the groove is reached the second time, when the cane is turned back

upon itself, with both ends uppermost to form a kink or loop, as shown at *a'* in Fig. 1 of the drawings. This kink is pressed into the groove, and one half of it is forced under the bend last 55 made in the cane, and the cane is then passed inward and downward entirely around the round and over the other half of the kink, and from thence to the opposite round, where the same operation is repeated, and is repeated back- 60 ward and forward until the frame is filled, when the weaving is commenced at right angles to the cane first woven. When the end of a cane is reached it is given only a half twist or kink, and the end is turned down into the groove 65 for an inch, more or less, and is held therein by the next succeeding cane, whose end is introduced under the woven canes in the groove in the same manner in which the end of the first cane was introduced into the leg. 70

In Fig. 2 I show a modified form of weaving the cane, in which the cane is passed from the inside of the round, under a strip, *b*, fitting loosely in the groove in said round, back upon itself over the strip *b*, and then down and entirely around the round, so as to press and hold the strip and the doubled portion of the cane around it into the groove. In this form of weaving the cane it is, however, necessary to give a twist in the cane under the round, 75 80 in order to bring the face of the cane upward on the exposed surface.

In the ordinary manner of weaving cane where the canes are passed around the frame-round the cane passes from round to round on 85 the bottom or rear side, as well as the top or face, and where the end of a cane comes upon the top or face the operator must necessarily cut off the end so as to effect the splice with the next cane under the chair. 90

In my invention the weaving is done entirely upon the exposed side of the frame, and the ends are secured in the rounds, avoiding the necessity of knotting or splicing, and saving nearly all of the cane heretofore on the rear or 95 bottom of the frame.

It will also be seen that in my invention only a single cane is handled at a time, said cane running back and forth across the frame until it is entirely used up. 100

I am aware that it is not new to so wind cane around a frame as to produce "close" weaving

without passing from side to side on both the top and bottom of the frame, and I do not broadly claim such invention.

What I claim is—

- 5 1. The combination, with the rounds B, having longitudinal grooves and forming the frame of a seat or back, of canes passed from round to round and doubled to fit into the grooves, and means, substantially as described, for se-
10 curing the looped portions of the canes in said grooves, substantially as described.

2. The combination, with a frame having grooved rounds, of canes passed across the frame from round to round, bent at the grooves in the rounds to form loops or kinks to fit in 15 said grooves, and passed back around said kinks or loops to secure them in place, sub-stantially as described.

ISAAC D. COMSTOCK.
